O. NICHOLS.
TIRE AND TUBE VULCANIZER.
APPLICATION FILED JAN. 12, 1920.
1,349,688. Patented Aug. 17, 1920.

UNITED STATES PATENT OFFICE.

OLIVER NICHOLS, OF MOUND VALLEY, KANSAS.

TIRE AND TUBE VULCANIZER.

1,349,688.

Specification of Letters Patent. Patented Aug. 17, 1920.

Application filed January 12, 1920. Serial No. 350,770.

To all whom it may concern:

Be it known that I, OLIVER NICHOLS, a citizen of the United States, residing at Mound Valley, in the county of Labette and State of Kansas, have invented a certain new and useful Improvement in Tire and Tube Vulcanizers, of which the following is a specification.

My invention relates to improvements in tire and tube vulcanizers.

The object of my invention is to provide a vulcanizer of the kind described which is simple in construction, cheap to manufacture, not liable to get out of order, durable and efficient in operation, and which may be readily operated by an inexperienced person.

A further object of my invention is to provide a vulcanizer having means for regulating the heating, as the circumstances may require, and which will not expose the material which is being vulcanized to direct contact with the steam employed for the heating.

A further object of my invention is to provide a tire vulcanizer and tube vulcanizer, with joint heating means arranged so that the vulcanizers may be used conjointly or one at a time.

My invention provides further novel heating means in the vulcanizer by which a uniform temperature may be obtained and economy in fuel combustion.

The novel features of my invention are hereinafter fully described and claimed.

In the accompanying drawing, which illustrates the preferred embodiment of my invention,

Figure 1 is a central vertical sectional view of my improved vulcanizer, the cover being shown closed.

Fig. 2 is a top view of the same, partly broken away, one of the connecting tubes which fill the air bags with steam being shown extended to the exterior of the vulcanizer.

Similar reference characters designate similar parts in the different views.

1 designates the casing of the tire vulcanizing chamber, which is preferably cylindrical and provided with a top having a hinged cover 2, and, preferably, provided with an interior asbestos lining 3.

The bottom of the casing 1 is supported by a cylindrical casing 4, having an interior

asbestos lining 5, and which incloses a boiler 6, exteriorly lined with asbestos 7 and having extending centrally vertically therethrough a passage 8 in which is located a downwardly converging deflector 60 9, spaced apart from the boiler 6.

The boiler 6 is supported by legs 11 and has located below it a suitable burner, such as a gas burner 12, which is supplied by means of a supply pipe 13 provided with a 65 regulating valve 14.

The products of combustion and heated air from the burner 12 pass upwardly through the passage 8 into a circular chamber 15 above the boiler 6, the top of which 70 chamber is the bottom of the casing 1. A smoke pipe 16 is connected to the chamber 15.

For heating the tire vulcanizing chamber, there is provided in the casing 1 a pipe 75 coil 17, which is located vertically closely adjacent to the inner wall of the casing and which has one end connected by a pipe 18 with the boiler 6, adjacent to the upper end thereof, and its other end connected by 80 a pipe 19 with the boiler 6 adjacent to the lower end thereof.

Steam from the boiler 6 passes upwardly through the pipe 18, thence through the coil 17, the condensed steam passing back 85 to the boiler by the pipe 19.

An adjustable pop valve 20 is connected by a pipe 21 to the pipe 18. This pop valve may be of any ordinary type which can be adjusted to blow off at different pressures. 90 By properly regulating the pop-off valve 20, the pressure in the boiler and coil 17 may be adjusted to suit the required conditions as to pressure and as to temperature in the casing 1. The top of the casing 1 95 may be provided with a thermometer 22, by which the interior temperature of the tire chamber may be ascertained.

In the tire chamber is mounted a removable perforate basket 23, preferably having 100 a bail 24, the basket being adapted to contain the tires which are to be vulcanized. Preferably the basket 23 rests upon a bed of sand 25 disposed upon the upper side of the bottom of the casing 1. Preferably 105 the asbestos lining 3 on the bottom of the casing 1 does not extend across that portion of the bottom which is directly above the heating chamber 15. By this arrangement, the heat from the chamber 15 is readily con- 110

ducted through the bottom of the casing 1 to the sand bed 25, thereby assisting the steam coil 17 and retaining an even temperature in the tire heating chamber.

5 Connected to the top of the coil 17 are a plurality of connecting pipes 26, having screw-threaded free ends adapted to be respectively connected with the usual air bags, which are commonly employed to inflate tubes which are to be vulcanized. Each tube 26 is provided with a shut-off valve 27, which is closed when the tube is not in use.

For vulcanizing inner tubes, I provide 15 a rectangular flat hollow box 28 of the ordinary type having at one end a steam discharge cock 29, Fig. 2. The box 28 is supported by a pipe 30, Fig. 1, which extends through the side wall of the casing 1 and is connected to the steam pipe 18. The pipe 30 also serves to supply steam to the interior of the closed box 28.

In the pipe 18 above the pipe 30 is a shut-off valve 31, the handle of which extends 25 through the side wall of the casing 1 so as to be accessible from the exterior of the casing. When the steam box 28 is to be used, the valve 29 is opened and the valve 31 closed or partly closed, according to 30 whether or not the tire chamber is to be used simultaneously with the use of the steam box 28. If no tires are to be cooked, the valve 31 is fully closed.

If tires are to be cooked simultaneously 35 with the use of the steam box 28 for vulcanizing tubes, the valve 31 may be opened sufficiently to permit of the desired flow of steam through the coil 17, such regulation of the valve 31 being dependent, of course, 40 upon the pressure in the boiler, and the latter, as above stated, may be regulated by the proper adjustment of the pop valve 20.

For supplying the boiler 6 with water, the pipe 19 is provided with connection to a 45 water supply pipe 32 having a shut-off valve 33.

In the operation of my invention, when it is desired to cook tires, the latter are provided with the usual inner air bags and 50 placed in the basket 23. The connecting pipes 26 are then respectively connected with the air bags, not shown, after which the valves 27 are opened.

The tire cooking chamber will be heated 55 by the steam coil 17 and the sand bed 25. The steam from the coil 17 will distend and heat the air bags in the tires by means of the connecting pipes 26. When the tires have been vulcanized, the cover 2 is swung 60 to the open position, the tubes 26 disconnected from the air bags, after which the basket 23 with the vulcanized tires therein

may be lifted by means of the bail 24 out of the tire cooking chamber.

When it is desired to vulcanize tubes on 65 the box 28, the valve 31 may be closed and the valve 29 opened, upon which steam from the pipes 18 and 30 entering the box 28 will heat the latter sufficiently for vulcanizing of the tubes which are mounted on the box 70 28 in the usual manner.

A water gage 34 of the ordinary type may be disposed at the exterior of the casing 4 and connected to the boiler 6 in the ordinary manner.

I do not limit my invention to the structure shown and described, as many modifications, within the scope of the appended claims, may be made without departing from the spirit of my invention.

What I claim is:—

1. In a vulcanizer, a tire heating chamber, a casing supporting said chamber, a boiler located in said casing, means in said casing for heating said boiler and said chamber, and a steam pipe connected with said boiler and having a coil located in said chamber.

2. In a vulcanizer, a tire heating chamber having an opening in its top and a cover for said opening, a steam pipe extending in 90 and adapted to heat said chamber, a tire container removable from said chamber through said opening, and a tube connected to said steam pipe and adapted to be connected with an inflating bag mounted in a 95 tire placed in said container.

3. In a vulcanizer, a tire heating chamber having an opening and a cover therefor, a steam pipe extending into and adapted to heat said chamber, means in said chamber 100 for containing tires and holding them out of contact with said steam pipe, and a tube connected with said steam pipe and adapted to be connected with an inflating bag in a tire placed in said containing means.

4. In a vulcanizer, a tire heating chamber, a boiler located below said chamber and having a passage therethrough adapted to convey heated products of combustion against the bottom of said chamber, and a 110 steam pipe connected with said boiler and extending into and adapted to heat said chamber.

5. In a vulcanizer, a tire heating chamber, a boiler, means by which heated products of 115 combustion heat the boiler and the bottom of said chamber, heat retaining means in said chamber on the bottom thereof, and a steam pipe connected with said boiler and extending into and adapted to heat said 120 chamber.

In testimony whereof I have signed my name to this specification.

OLIVER NICHOLS.
